UNITED STATES PATENT OFFICE.

HENRY G. RUNNE, OF ROCHESTER, NEW YORK.

VEHICLE.

1,232,434.

Specification of Letters Patent. Patented July 3, 1917.

Application filed January 29, 1917. Serial No. 145,063.

To all whom it may concern:

Be it known that I, HENRY G. RUNNE, of Rochester, in the county of Monroe and State of New York, have invented certain 5 new and useful Improvements in Vehicles; and I do hereby declare the following to be a full, clear, and exact description of the same, reference being had to the accompanying drawings, forming a part of this 10 specification, and to the reference characters marked thereon.

My invention relates to improvements in vehicles and has for its object to provide, more particularly, a toy vehicle, the body 15 or seat of which may be adjusted to relatively different heights to accommodate children of different ages and sizes, whereby the rider's feet may be employed in engagement with the surface upon which the 20 vehicle travels as a means for propelling the same. A further object of the invention is to provide an improved and adjustable steering post and rear body support for a vehicle, whereby the seat or body may 25 be raised or lowered at both ends when desired. To these and other ends the invention consists in certain improvements and combinations of parts, all as will be hereinafter more fully described, the novel features being pointed out in the claims at the 30 end of the specification.

In the drawings:

Figure 1 is a side elevation embodying one form of the invention;

35 Fig. 2 is a similar view showing the body of the vehicle adjusted to its lowermost position;

Fig. 3 is an enlarged horizontal sectional view through the rear wheels and bolster 40 showing the manner of mounting the axle thereon;

Fig. 4 is a top plan view of the vehicle;

Fig. 5 is a bottom plan view of the same;

Fig. 6 is an enlarged sectional elevation 45 through the seat board at the point where the steering post passes therethrough;

Fig. 7 is a sectional view taken on line *a—a* of Fig. 6, and

Fig. 8 is a detail perspective view of the 50 steering post key for holding the body in proper position upon the steering post.

Similar reference characters throughout the several views indicate the same parts.

The purpose of the present invention is 55 to provide a toy vehicle, of the velocipede type, and one on which the front of the

body or seat board may be readily adjusted to different heights upon the steering post by means of a removable key or locking plate, for holding said body thereon; the rear end of the body being raised or lowered through the medium of a bolster or support pivotally connected therewith which may be adjusted from a vertical to various inclined positions by means 60 of an adjustable brace rod extending upwardly from a point near the bottom of the bolster to connect with a brace rod holder upon said body.

In the drawings I have shown a seat 70 board or body member 10, preferably constructed of one piece of material, the rear end of which forms the seat 11 and the front end being apertured to receive the inclined steering post 12, as clearly shown 75 in Fig. 6. The body is considerably narrowed in front of the seat as shown in Fig. 4 to provide ample clearance for the legs of the occupant of the vehicle when propelling the same. Beneath the body and 80 secured longitudinally thereon is a bar or cleat 13 having at its front end a transverse aperture 14 and at its rear end a series of transverse apertures 15, as shown in Figs. 1 and 2, which are adapted to receive the 85 forward end 16 of the brace rod 17 to secure it in various positions of adjustment, the number of said apertures being varied as may be desired. The rear of the brace rod 17 is loosely or pivotally connected, 90 preferably with the rear axle 18, which is extended through the bottom of the bolster or body support 19, said bolster being notched at 20 to provide clearance for the rear end of said brace rod in order that the 95 same may be directly connected with the axle. Upon the ends of the axle are mounted the rear wheels 21, said axle being held against longitudinal displacement preferably by the cotter pin 22.

100 The bolster 19 is pivotally connected with the body beneath the seat 11 preferably by means of the hinges 23. The lower end of the steering post is bifurcated to receive the front wheel 24 journaled on the axle 25, 105 while the upper end of said post is provided with suitable operating handles 26 as shown in Fig. 4. The steering post is provided with a series of annular grooves or recesses 30 adapted to receive a locking key 32 by 110 means of which the height of the body may be varied. Secured beneath the front end

of the vehicle body and abutting the cleat 13 is a bearing for the steering post, comprising the upper and lower plates 27 and 28 through which the steering post extends 5 preferably at an angle to the vertical as shown in Fig. 6. The bearing plates have their adjacent faces beveled which lie in a plane extending at right angles to the steering post, said plates being secured to 10 the body by fastening devices such as the screws 29.

A recess or pocket 31 is formed in the upper face of the lower bearing plate 28 to receive the lock plate or body supporting 15 key 32 which is inserted in the pocket from the rear of the steering post. The lock plate or supporting key is cut or bifurcated at its front end, as shown in Fig. 8, the curved edge 33 thereof being made semicircular in 20 shape to conform to the curvature of the reduced cylindrical portions 34 of the steering post at the base of the grooves 30, whereby the maximum bearing surface is provided between the lock plate and post to 25 prevent accidental displacement of the body upon the post, the latter being rotatable upon the plate. The locking plate is of a thickness substantially equal to the width of the grooves 30 so as to fit rather snugly 30 therein to prevent undue movement of the front end of the seat board upon said steering post. The back of the locking plate is provided with the spaced upstanding lugs or members 35 which extend upon opposite 35 sides of the cleat 13 when the plate is in locking position upon the steering post, said plate being held against displacement by the pin or stud 36 extended through the cleat 13 and arranged to project upon opposite 40 sides thereof in contact with said lugs.

The seat board or body 10 may be readily raised or lowered by removing the locking plate 32 and shifting the steering post upwardly or downwardly as the case may be, 45 until the desired groove is brought into alignment with the recess 31, at which time the locking plate is re-inserted in said recess to engage the post within said groove, being understood that the post is free to 50 rotate upon its bearings and upon the plate when the same is in locking engagement therewith. The adjustment of the rear end of the body is effected by moving the position of the brace rod 17 forwardly or rearwardly, thereby shifting the position of the bolster or support 19 until the seat is brought to the desired horizontal position. 55

I claim as my invention:

1. The combination with a vehicle body, 60 of a plurality of wheels for supporting the

same, a steering post carried by one of the wheels having a groove formed thereon, and a removable member upon the body engaging the steering post within the groove to support the body upon said steering post. 65

2. The combination with a vehicle body, of a plurality of wheels for supporting the same, a steering post carried by one of the wheels and rotatably mounted upon the body and a plate upon the body engaging 70 the steering post within a groove formed thereon, said plate serving to support one end of the body.

3. The combination with a vehicle body, of a plurality of wheels for supporting the same, a steering post carried by one of the wheels provided with a plurality of grooves, and a removable body supporting member arranged to engage the steering post within 75 said grooves for supporting said body at 80 relatively different heights upon said steering post.

4. The combination with a vehicle body, of a plurality of wheels for supporting the same, an inclined steering post carried by 85 one of the wheels having a plurality of grooves formed thereon, a member upon the body movable into and out of the grooves for supporting one end of the body at varying heights upon said post and a body supporting member upon the remaining wheels adjustable to support the other end of said body at relatively different heights. 90

5. A vehicle comprising a body, a pivotal support for the same, wheels revoluble upon the support, means for adjusting the support upon the body to raise and lower one end of the latter, an inclined steering post having a plurality of annular grooves formed thereon, a wheel revoluble upon the 100 post, a bearing upon the body in which said post is rotatably mounted, a recess formed in the bearing transversely of the longitudinal axis of the post and a plate insertible in the recess to engage the post in said 105 grooves for supporting said body upon said post at relatively different heights.

6. A vehicle comprising a body, a plurality of wheels for supporting the same, a steering post carried by one of said wheels 110 provided with a plurality of annular grooves, a bearing on the body upon which said post is rotatably mounted, a recess formed in said bearing and a key insertible in said recess to engage the post in each of said grooves whereby the body may be adjusted to various positions upon the steering post. 115

HENRY G. RUNNE.
